UNITED STATES PATENT OFFICE.

NELSON T. CLINE AND ROBERT M. LONG, OF PITTSBURGH, PENNSYLVANIA.

LUBRICATING DEVICE.

1,265,748.

Specification of Letters Patent. Patented May 14, 1918.

Application filed January 31, 1918. Serial No. 214,572.

To all whom it may concern:

Be it known that we, NELSON T. CLINE and ROBERT M. LONG, citizens of the United States of America, residing in Pittsburgh,

5 in the county of Allegheny and State of Pennsylvania, have invented certain new and useful Improvements in Lubricating Devices, of which the following is a specification.

10 This invention relates to lubricating devices, particularly designed for the compression cylinders of air compressors, but it is to be understood that the device can be used for any purpose wherein it is found applicable, and the invention has for its object to provide, in a manner as hereinafter set forth, a lubricator that will satisfactorily supply a lubricant to the compression cylinder of an air compressor, more particularly, a cylinder of the cross-compound type of air compressor.

15 It is well known that railroad companies have experienced great difficulty in maintaining the high efficiency in the air brake equipment, which is due primarily to the fact that the pistons in the compression chambers were not being properly lubricated, due to the fact that the compression chambers were either being flooded with the lubricant or not receiving the necessary quantity of lubricant at the proper time. Under such conditions the air-discharge of the compressor would become clogged up with carbon preventing the free discharge 20 of air to the main reservoir, thus causing the compressor to heat and become defective, the lubricating device forming the subject matter of this invention is not only designed to overcome the objections cited, but further 25 provides a lubricating device, which is simple in its construction, inexpensive to manufacture, readily applied at minimum expense, conveniently set-up with respect to the compressor without the employment of extra skill to apply or operate it, is adapted 30 for use in single or cross-compound compressors, and can be extended in the engine-cab, making it convenient for the engineer to handle when required.

35 A further object of the invention is to provide a lubricating device, in a manner as hereinafter set forth, which is economical in its use, overcoming waste of oil and prolonging the life of the compressor, thereby

saving heavy expense to railroad companies 55 in the way of maintenance which has become a big idea of expense.

Further objects of the invention are to provide a lubricating device, in a manner as hereinafter set forth, whereby the feed of 60 the lubricant can be controlled so that when the desired amount is supplied and furthermore to provide the device with means whereby the feed of the lubricant to the compressor is had only when the compressor is 65 in operation, thereby eliminating all possibility of the compressor being flooded with oil.

A further object of the invention is to provide a lubricating device in a manner as 70 hereinafter set forth, whereby the lubricant is atomized and distributed uniformly over the walls of the cylinder of the compressor chamber, thereby insuring a satisfactory lubrication of all parts at all times.

75 With the foregoing and other objects in view this invention consists of the novel construction, combination and arrangement of parts, as hereinafter more specifically described and illustrated in the accompanying 80 drawings, wherein is shown an embodiment of the invention, but it is to be understood that changes, variations and modifications can be resorted to which come within the scope of the claims hereunto appended.

85 In the drawings wherein like reference characters denote corresponding parts throughout the several views:

Figure 1 is an elevation of a cross-compound air compressor showing the adaptation therewith of a lubricating device in accordance with this invention.

90 Fig. 2 is a sectional detail illustrating the lubricating feed pipe for the high pressure cylinder.

95 Fig. 3 is a cross sectional view of the high and low pressure cylinders of the air compressor illustrating the lubricant feed pipes opening into the inlet passages of said cylinders.

100 Fig. 4, is a vertical sectional view of the lubricant storage receiver.

105 Fig. 5 is a vertical sectional view of the valvular element for controlling the feed of the lubricant.

Fig. 6 is a section on line V—V, Fig. 5.

Fig. 7 is an elevation of the feed pipe coupling.

Referring to the drawings in detail 1 denotes an air compressor, of the cross-compound type, and which includes a high pressure cylinder 2, and a low pressure cylinder 3. The cylinder 2 has an air inlet passage 4, and the cylinder 3 an air inlet passage 5.

Opening into cylinder 2 at the rear of the inlet passage 4, is a lubricant feed pipe 6, for the high pressure cylinder 2. The outer end of the pipe 6, is provided with a valve casing 7, having a check-valve 8, arranged therein and the function of the valve 8, is to close the pipe 6, to a supply of lubricant during the supply of lubricant to the low pressure cylinder 3.

Extending from the casing 7, is a pipe branch 9, which is attached to a Y-coupling, the branches of which are indicated at 10, 11 and 12.

Connected to the branch 11, is a lubricant feed pipe 13, which opens into cylinder 3 at the rear of the air inlet passage 4, of the low pressure cylinder 3.

Connected to the branch 12, of the Y-coupling is an elongated lubricant supply pipe 14, preferably extending into the engine-cab as indicated at 15.

Mounted on the upper end of the supply pipe 14, is a valve casing 15', having a seat 16, for a spring controlled check valve 17. The casing 15', has a partition wall 18, formed with outlet ports 19 and which also constitutes a stop for the lower end of the valve stem 20, of the valve 17. The spring 21, which controls the valve 17, is interposed therebetween and the partition wall 18, and acts as a means for normally closing the inlet 22, of the casing 15'. The inlet 22, is formed from an exteriorly threaded nipple 23.

Arranged above the check-valve casing 15', is an annular receptacle 24, which provides a lubricant receiver or reservoir 25. The bottom of the receptacle 24, is formed with a central outlet passage 26, and a depending cylindrical peripherally threaded stem 27, having a central bore 28, which registers with the passage 26. The stem 27, is connected to the nipple 23, by a union 29, which permits of disconnecting the casing 15', from the receptacle 24, when desired.

The bottom of the receptacle 24, centrally thereof, has formed integral with its upper face a vertically disposed annular member 30, which provides a well 31. The member 30, at its upper end is closed by a removable plug 32, and said member 30, has a transverse opening or port 33, intermediate its upper and lower ends, for establishing communication between the receiving chamber or reservoir 25.

The receptacle 24, is closed at its top, by a removable flanged cap 34, having a central opening 35, in which is secured a lubricant conducting pipe 36, leading from a lubri-

cant supply, as shown a lubricant cup 37, of any suitable type capable of being adjusted to any feed desired.

The receptacle 24, intermediate its upper and lower ends is provided with an overflow opening 38. The receptacle 24, is mounted on a support 39, at a point whereby the contents thereof can be heated, if desired, and is fixedly secured through the medium of a clamping nut 40, carried by the stem 27, and abutting against the support 39.

By the arrangement shown the lubricant is alternately supplied to the low and high pressure cylinders of the compressor on an intake stroke of the pistons in said cylinders. On a discharge stroke of the pistons, the latter moving upwardly, in the high pressure cylinder the check valve 8, will be seated and prevent the air from the high pressure cylinder being forced into the pipe 14, or the low pressure cylinder. On an intake stroke of the piston in the low pressure chamber, the piston moving downwardly, the lubricant will be drawn into the low pressure cylinder, but will be arrested from entrance into the high pressure cylinder, due to the seating of the valve 8.

As the valve 17, is normally seated the lubricant can only be supplied to the pipe 14, on a suction stroke of either piston, in the compression cylinders. Any back pressure from the low pressure cylinder will also tend to assist the maintaining of the valve 17, closed so that there is no possibility of any back pressure blowing the lubricant out of the reservoir 25.

Owing to the arrangement shown the lubricant is fed in the desired quantity to prevent waste and also flooding of the compression cylinders.

The discharge stroke, upward, of the piston of the low pressure cylinder will discharge the air, not only through the outlet passage of said cylinder but also through the pipe 13, and assist in feeding the lubricant, in connection with a suction stroke of the piston in the high pressure cylinder, to the high pressure cylinder. Under such conditions the pistons in the high pressure cylinders are utilized to cause a feed of lubricant to the high pressure cylinder.

What we claim is:

1. A lubricating device for air compressors comprising a lubricant supply pipe having a casing provided with a normally seated check valve to close said pipe to supply, lubricant feed pipes connected with the supply pipe and leading to the high and low pressure cylinders of a compressor and providing means whereby the lubricant supplied to the supply pipe on the unseating of said valve will be fed to the high pressure cylinder by the action of the pistons in said cylinders, and a receptacle having therein a reservoir and a well, said well having a

port in its side for establishing communication with the reservoir, said reservoir connected with a lubricant source, and said receptacle connected with said casing and having means for establishing communication between the well and the casing for feeding lubricant to the latter.

2. A lubricating device for air compressors comprising a lubricant supply pipe having a casing provided with a normally seated check valve to close said pipe to supply, and lubricant feed pipes connected with the supply pipe and leading to the high and low pressure cylinders of a compressor and providing means whereby the lubricant supplied to the supply pipe on the unseating of said valve will be fed to the high pressure cylinder by the action of the pistons in said cylinders, that feed pipe leading to the high pressure cylinder provided with a check valve for closing it during the feed of the lubricant through the other feed pipe, from the supply pipe to the low pressure cylinder caused by a suction stroke of the piston in the low pressure cylinder, and a receptacle having therein a well, said well having a port in its side for establishing communication with the reservoir, said reservoir connected with a lubricant source, and said receptacle connected with said casing and having means for establishing communication between the well and the casing for feeding lubricant to the latter.

3. A lubricating device for air-compressors comprising a Y-shaped coupling, a supply pipe attached to one of the inclined legs of said coupling, a feed pipe connected to the other of the inclined legs of and leading to one of the compression chambers of the compressor, and a feed pipe connected with the horizontal leg of the coupling and having interposed therein a check valve, said last mentioned leg leading to another of the compression chambers of the compressor.

4. A lubricating device for air-compressors comprising a Y-shaped coupling, a supply pipe attached to one of the inclined legs of said coupling, a feed pipe connected to the other of the inclined legs of and leading to one of the compression chambers of the compressor, and a feed pipe connected with the horizontal leg of the coupling and having interposed therein a check valve, said last mentioned leg leading to another of the compression chambers of the compressors, and a means to provide a normally seated and suction operated check valve carried by said supply pipe and normally cutting off feed of lubricant to the supply pipe.

5. A lubricating device for air-compressors comprising a Y-shaped coupling, a supply pipe attached to one of the inclined legs of said coupling, a feed pipe connected to the other of the inclined legs of and leading to one of the compression chambers of the

compressor, and a feed pipe connected with the horizontal leg of the coupling and having interposed therein a check valve, said last mentioned leg leading to another of the compression chambers of the compressors, a means to provide a normally seated and suction operated check valve carried by said supply pipe and normally cutting off feed of lubricant to the supply pipe, and a receptacle having a reservoir and a closed well, the latter having port for establishing communication with the said reservoir, and means for connecting said receptacle with said supply pipe and for establishing communication between the well and said valvular means.

6. A lubricating device for air-compressors comprising a Y-shaped coupling, a supply pipe attached to one of the inclined legs of said coupling, a feed pipe connected to the other of the inclined legs of and leading to one of the compression chambers of the compressor, and a feed pipe connected with the horizontal leg of the coupling and having interposed therein a check valve, said last mentioned leg leading to another of the compression chambers of the compressors, a means to provide a normally seated and suction operated check valve carried by said supply pipe and normally cutting off feed of lubricant to the supply pipe, and a receptacle having a reservoir and a closed well, the latter having port for establishing communication with the said reservoir and means for connecting said receptacle with said supply pipe and for establishing communication between the well and said valvular means, means for establishing communication between said reservoir and a lubricant source, and said receptacle having means to provide an overflow discharge for said reservoir.

7. A lubricating device for air-compressors comprising a supply pipe, means connected with one end of said pipe for feeding lubricant to the compression chamber of a compressor, a casing mounted on the other end of said pipe and having a suction operated and normally seated check valve to normally shut off supply of said pipe, said valve unseated on the suction stroke of the compressor acting through said means and supply pipe to cause a supply of lubricant to said pipe and a feed of lubricant through said means to said chamber, means to provide a reservoir having arranged therein a closed well provided with a port in its side wall to establish communication with the reservoir, and means for establishing communication between said well and said casing.

8. A lubricating device for air-compressors comprising a supply pipe, means connected with one end of said pipe for feeding lubricant to the compression chamber of a compressor, a casing mounted on the other

end of said pipe and having a suction operated and normally seated check valve to normally shut off supply of said pipe, said valve unseated on the suction stroke of the compressor acting through said means and supply pipe to cause a supply of a lubricant to said pipe and a feed of lubricant through said means to said chamber, means to provide a reservoir having arranged therein a closed well provided with a port in its side wall to establish communication with the reservoir, and means for establishing communication between said well and said casing, said reservoir having its side provided with an overflow port.

9. A lubricating device comprising a pair of lubricant feed pipes adapted to open into the compression chambers of an air compressor, a supply pipe, a Y-shaped coupling

interposed between and connected to said pipes, and a check valve mounted in one of said feed pipes.

10. A lubricating device comprising a pair of lubricant feed pipes adapted to open into the compression chambers of an air compressor, a supply pipe, a Y-shaped coupling interposed between and connected to said pipes, and a check valve mounted in one of said feed pipes, and a normally seated check valve carried by the supply pipe.

In testimony whereof we affix our signatures in the presence of two witnesses.
